Patented Sept. 16, 1919.

FIG. 1.

FIG. 2.

FIG. 3.

FIG. 4.

WITNESS:

W. Lewis Coop

INVENTOR.

Ora L. Gambrel
BY
Jno. G. Powell,
ATTORNEY.

UNITED STATES PATENT OFFICE.

ORA L. GAMBREL, OF DENVER, COLORADO.

RAZOR-STROPPE.

1,316,228.

Specification of Letters Patent. Patented Sept. 16, 1919.

Application filed January 16, 1918. Serial No. 212,025.

To all whom it may concern:

Be it known that I, ORA L. GAMBREL, citizen of the United States, and resident of the city and county of Denver and State of

5 Colorado, have invented certain new and useful Improvements in Razor-Stroppers, of which the following is a full, clear, and exact description, such as will enable others skilled in the art to which the invention ap-

10 pertains to make and use the same.

My invention relates to improvements in razor blade stroppers, and the invention has for its object, the provision of means for mechanically actuating the blade in engagement with the strop, and for holding the blade in engagement with the strop until each stroke on the strop has been completed.

15 Another object of the invention is to provide a razor blade stropping device by means of which any safety razor blade of ordinary use may be sharpened.

Another object of the invention is to provide a razor blade stropper which is operable for automatically reversing the blade 20 at each operation at the beginning of the stroke upon a sharpening strop.

Another object of the invention is to provide a razor blade stropping device which is operable by frictional engagement with 25 a sharpening strop for automatically shifting the opposite sides of the razor blade into engagement with the strop.

Another object of the invention is to provide a razor blade stropping device which 30 is of simple construction, efficient in operation, and adaptable for stropping all safety razor blades of ordinary use.

With these and other objects in view, the invention will now be described with reference 35 to the accompanying drawing, which forms a part hereof.

In this drawing, Figure 1 is a perspective view of the stropping device; Fig. 2 is a plan view of the stropping device, illustrating 40 the manner in which the same engages with a sharpening strop; Fig. 3 is a cross-sectional view of the stropping device taken on the line 3—3 of Fig. 2; and Fig. 4 is a longitudinal sectional view of the stropping 45 device.

Corresponding and like parts are referred to in the following description, and indicated in all the views of the accompanying drawing by the same reference characters.

Let the numeral 5 designate the handle 55 of the stropping device, the same being preferably formed of metal bent to form a channel 6. The material from which the handle 5 is formed, is extended from the handle 5 at one extremity into a flat segmental part 7. This 60

flat part 7 is cut out to form an opening 8 therethrough of segmental shape. Rack teeth 9 are formed upon the flat part 7 at the forward extremity of the segmental opening 8.

A razor blade holding member 10 is fixedly 65 secured upon a pin 11, which said pin 11 is journaled in ears 12, said ears 12 being cut out of an oscillating strip 13. This oscillating strip 13 is fulcrumed intermediate its extremities but nearer its rear ex-

tremity, within the channel 6 of the handle 5, as shown at 14. This oscillating strip 13 is disposed on the under surface of the flat part 7, and the ears 12 thereof are cut out of and formed by the material of the oscillat-

70 ing member 13, said ears 12 being bent at right angles to the oscillating strip 13, and extended through the opening 8 in the flat part 7. One extremity of the pin 11 is pro-

vided with a pinion 15 fixedly secured 75 thereon and meshing with the rack teeth 9. One extremity of a balance spring 16 is pivotally connected with the rear extremity of the oscillating strip 13, as shown at 17,

and the other extremity of the balance 80 spring 16 is fixedly secured in a block 18. This balance spring 16 is disposed so that its tension will be exerted to normally main-

tain it in line with the longitudinal axis of the stropping device. The balance spring 85 16, as well as the fastening block 18, is positioned in the channel 6 of the handle 5. The fastening block 18 is secured within said channel by means of fastening de-

90 vices 19.

The forward extremity of the oscillating strip 13 is bent rearwardly to form a part 95 20, which is adapted to frictionally engage with the under side of the sharpening strop 25. This part 20 is bifurcated, as shown at 100

21, forming two fingers 22 and 23. The extremities of these fingers 22 and 23 are curved outwardly, as shown at 24, whereby the part 20 is guided over the edge of the 5 strop, causing the strop to be readily received between the part 20 and the body of the oscillating strip 13.

The razor blade holding part 10 is formed by doubling a strip of spring material upon 10 itself, whereby two opposing sides 26 and 27 are formed, the edges of said sides 26 and 27 being bent so that they will come together and engage the opposite sides of a blade 28, as shown at 29. This spring material forming the razor holding part 10 is looped around the journal pin 11, as shown at 30, the said material being so tightly engaged with the journal pin 11 that it is fixed against movement independently of 15 said journal pin 11. The two sides 26 and 27 of the blade holding member 10 are separated from each other at a point between the journal pin 8 and the outer edge of said member, as shown at 31, whereby a razor 20 blade having a bead upon one edge, may have its bead received in the space so formed between the sides 26 and 27.

In operation, the blade 28 is gripped between the sides 26 and 27, and as the stropping device is moved backward and forward upon the strop, the blade holding member 10 is oscillated alternately, causing the opposite sides of the blade 28 to engage with the strop. The fingers 22 and 23 of the part 20 30 will frictionally engage with the under side of the strop 25, whereby, as the stropping device is moved upon the strop, the oscillating strip 13 will be swung upon its fulcrum 14 to the limit of its movement in one direction, the ears 12 forming stops to the oscillating movement of the oscillating strip 13. The balance spring 16 serves to normally 35 maintain the oscillating strip 13 in a position parallel with the flat part 7 of the device, whereby the razor blade holding member 10 is maintained in an upright position, thereby holding the blade 26 out of engagement with the strop until the stroking movement of the device is commenced. As the 40 device is moved in one direction on the strop, the oscillating strip 13 is caused to move in the reverse direction against the tension of the balance spring 16, and the rack teeth 9, by their action upon the pinion 45 15 will cause the blade holding member 10 to swing in the direction opposite to the direction in which the stroke of the device is being made, whereby the blade 28 will be engaged with the strop 25. When a stroke 50 of the device is commenced in the opposite direction, the swinging movement of the blade holding member 10 will be reversed.

While I have described and illustrated herein a specific form of my invention, it is 55 understood that I am not limited thereto,

and that the same may be modified and varied without departing from the spirit of the invention or the scope of the appended claims.

Having thus described the invention, what 70 I claim and desire to secure by Letters Patent, is:—

1. A razor blade strop, comprising a body portion having an opening therethrough, an oscillating strip fulcrumed on 75 said body portion, and a blade holding member carried by said oscillating strip and extended through said opening, said blade holding member adapted to be actuated by said oscillating strip to cause said blade 80 holding member to swing to a position for engaging the razor blade with a sharpening strop.

2. A razor blade strop, comprising a body portion, an oscillating strip fulcrumed 85 on said body portion, and having one extremity bent to form a part adapted to engage with the under side of a sharpening strop, the body portion having a flat part disposed above said oscillating strip, said 90 flat part having an opening therein, a blade holding member journaled upon said oscillating strip and received through said opening, said flat part having rack teeth thereon, a pinion carried by said blade holding member 95 and meshing with said rack teeth, and a balance spring connected with one extremity of said oscillating strip whereby the latter is held parallel with said flat part.

3. A stropping device, comprising a body 100 part having a flat portion at one extremity, said flat portion having an opening therein, an oscillating strip disposed on the under side of said body part and fulcrumed thereto, a blade holding member fulcrumed on 105 said oscillating strip and passed through the opening of said flat portion, said oscillating strip having its outer extremity bent rearwardly and adapted to engage with the under side of a sharpening strop, a balance 110 spring operatively connected with said oscillating strip normally holding said oscillating strip parallel with said flat portion, rack teeth on said flat portion and a pinion on said blade holding member meshing with 115 said rack teeth.

4. A stropping device, comprising a body part forming a channel handle and a flat portion at one extremity of said handle, said flat portion having an opening therein, an 120 oscillating strip disposed on the under side of said body part and fulcrumed thereon, the said oscillating strip having right angle parts thereon extending through said opening of the flat portion, a blade holding member 125 fulcrumed in said right angle parts, said oscillating strip having its outer extremity bent rearwardly and adapted to frictionally engage with the under side of the sharpening strop, a balance spring arranged par- 130

allel with the flat portion and operatively connected with one extremity of said oscillating part for normally holding said oscillating part parallel with said flat portion, 5 rack teeth on said flat portion and a pinion on said blade holding member meshing with said rack teeth, whereby the said blade hold-

ing member is maintained in an upright position under the influence of the balance spring.

10

In testimony whereof, I hereby affix my signature.

ORA L. GAMBREL.
